United States Patent Office

Des. 222,253

Patented Oct. 12, 1971

222,253

STORAGE BIN

Clarence B. Coleman and Harry R. Kattelmann, Oakland,
Calif., assignors to Fabricated Metals, Inc.

Filed June 8, 1970, Ser. No. 23,372

Term of patent 14 years

Int. Cl. D23—01

U.S. Cl. D23—2

FIG. 5

FIG. 6

FIG. 3

FIG. 4

FIG. 2

FIG. 1 is a top plan view of a storage bin embodying our new design;

FIG. 2 is a bottom plan view thereof;

FIG. 3 is a rear elevational view thereof, the front being the same as the rear shown;

FIG. 4 is a perspective view taken from the bottom and front thereof;

FIG. 5 is a side elevational view thereof, the opposite side being the same as the side shown; and

FIG. 6 is a perspective view taken from the top and front thereof.

We claim:

The ornamental design for a storage bin, as shown and described.
